UNITED STATES PATENT OFFICE.

NATHAN C. JOHNSON, OF ENGLEWOOD, NEW JERSEY, ASSIGNOR TO RAYMOND CONCRETE FILE COMPANY, OF NEW YORK, N. Y., A CORPORATION OF NEW JERSEY.

APPARATUS FOR ERECTING CONCRETE PILES.

1,181,141.

Specification of Letters Patent.

Patented May 2, 1916.

Application filed July 10, 1914, Serial No. 850,105. Renewed August 5, 1915. Serial No. 43,902.

To all whom it may concern:

Be it known that I, NATHAN C. JOHNSON, a citizen of the United States, residing at Englewood, in the county of Bergen and 5 State of New Jersey, have invented certain new and useful Improvements in Apparatus for Erecting Concrete Piles, of which the following is a full, clear, and exact description.

10 In erecting concrete piles molded in place—that is, in which a hole is first driven into the ground and the plastic material then filled in—it is very desirable that the integrity of the resulting pile or column be maintained as by leaving in the ground a thin 15 metal or other shell which shall resist the inward pressure of the surrounding earth until the plastic material is firmly set. One form of such shell is shown in U. S. patent 20 to Raymond No. 589,026, dated August 31, 1897. In some cases it has been found desirable to have a pedestal or enlarged footing on such piles. Usually this has been accomplished by making the pile shell open 25 at the lower end and withdrawing it gradually as the plastic material is filled in. This, however, has been open to the serious objection that water or other foreign matter seeping in as the pile shell is removed tends 30 to affect the integrity or stability of the column or pile, and consequently to impair or defeat its utility.

By my present invention I can erect mold-in-place piles with an enlarged footing or 35 pedestal, at the same time avoiding these and other objections.

In the drawings, Figure 1 represents in longitudinal section a pile shell in place in the earth showing my apparatus partly in 40 section and partly in elevation; Fig. 2 is a similar view after the pedestal or enlarged footing is substantially formed. Fig. 3 is a cross section on the line A—A of Fig. 1, and Fig. 4 is a cross section on the line 45 B—B of Fig. 2.

In the drawings 1 represents a pile shell which may be of thin sheet metal, papier-mâché or the like, which is driven into the ground in a manner well understood in the 50 art.

2 is a container or cartridge which, after the pile shell has been driven into place, is filled with plastic concrete and let or dropped down into the pile shell as hereinafter described. Attached to the lower

end of the cartridge 2 is a head 3, to which are hinged knives 4, the arrangement being such that when pressure is applied, the knives will be forced outwardly to the position shown in Fig. 2, and when the cartridge 60 2 is drawn upward the knives will swing back into the cavity of the pile shell. At the bottom the knives rest on a head 6 having inclined upper surfaces, as shown, and supported within said head 3, as by a sliding rod 5, so as to have vertical movement within the cartridge head. The head 6 is provided with grooves to permit its withdrawal through the plastic cementitious material.

In the use of my device the cartridge and head are made sufficiently smaller than the main diameter of the pile shell, so that they may be easily inserted into and removed therefrom. Having been filled with plastic 75 concrete and inserted into the pile shell, the device is dropped to the bottom thereof from a height of say 5 or 6 feet, when the weight and impact of the plastic concrete will throw the knives 4 outwardly, so that 80 they will cut or burst through the thin pile shell and permit the plastic concrete to flow outwardly so as to form a footing or pedestal in the manner indicated in Figs. 2 and 4, and at the same time seal off the holes in 85 the pile shell against seepage. This action may, if desired, be increased by pressure applied on the top of the concrete as by a tamper or other suitable means. It will be observed from Fig. 2, the cutting of the pile 90 shell only extends upward for a short distance, leaving the main part of the pile shell intact and so preserving the integrity of the column. At the lower part there is no opportunity for water or mud to seep 95 into the pile shell, for the force of the impact on dropping the cartridge and the pressure exerted by the pile driver or other means will force the plastic concrete outward and thereby minimize and obviate to 100 every practical extent the seepage of water into the column. Immediately after the pedestal has been formed, as described, the cartridge 2, with its attached head and knives, may be withdrawn from the pile 105 shell and the act of pulling it upward will end to swing the knives 4 inward. The balance of the pile or column may then be filled in the ordinary manner if the contents of the cartridge have been insufficient for 110

that purpose. Preferably I fasten the knives 4 with a light wire or cord 7 before dropping, this fastening being of such character as will be broken by the impact, to 5 permit the knives to perform their function.

What I claim as my invention is:

1. In an apparatus for forming pedestal piles, the combination with a pile shell, of a container for a charge of plastic concrete, 10 a head upon the container, cutting devices hinged at the lower end of said container and adapted to be actuated by the said head and means for withdrawing said container from the pile shell.
- 15 2. In an apparatus for forming piles within a pile shell, the combination of a container for plastic concrete of less diameter than the pile shell, a head upon the container, a series of cutting devices arranged 20 to be swung outwardly by the impact of the said head upon the container against the lower end of the pile shell, and means for withdrawing the container from the pile shell.
- 25 3. An apparatus for molding piles with enlarged footing, comprising a pile shell of thin material driven into the ground, a container for plastic material adapted to move freely within the pile shell and means operated by the impact of said container against the bottom of the pile shell for cutting the 30 foot of the latter so as to permit a part of the contents of the container to be discharged through the lower end of the pile shell.
- 35 4. An apparatus for forming piles, comprising, in combination, a pile shell driven

into the ground, a container for plastic material adapted to move freely within the pile shell, a head secured in the lower end 40 of the container adapted to move toward and away therefrom, a series of cutting devices pivotally mounted upon the lower end of the container and registering with the said head member adapted to be forced outwardly 45 when the head member strikes the bottom of the pile shell thereby cutting the foot of the latter so as to permit a part of the contents of the container to be discharged through the lower end of the pile shell. 50

5. An apparatus for forming piles, comprising, in combination, a pile shell driven into the ground, a container for plastic material adapted to move freely within the pile shell, a head secured in the lower end of the 55 container adapted to move toward and away therefrom, grooves in the said head, a series of cutting devices having one end pivotally secured upon the lower end of the container and the other end in register with the said head member adapted to be forced outwardly when the head member strikes the bottom of the pile shell thereby cutting the 60 foot of the latter so as to permit a part of the contents of the container to be discharged through the lower end of the pile shell. 65

In testimony whereof I affix my signature in the presence of two subscribing witnesses.

NATHAN C. JOHNSON.
